UNITED STATES PATENT OFFICE.

CARL GUSTAFSON, OF SÖDERTELJE, AND KNUT APPELGREN, OF LJUSNE, SWEDEN.

FORCE-FEED LUBRICATOR.

1,308,417.

Specification of Letters Patent.

Patented July 1, 1919.

Application filed August 6, 1918. Serial No. 248,539.

To all whom it may concern:

Be it known that we, CARL GUSTAFSON, a citizen of the Kingdom of Sweden, residing at Södertelje, Sweden, and KNUT APPELGREN, a citizen of the Kingdom of Sweden, residing at Ljusne, Sweden, have invented a new and useful Improved Force-Feed Lubricator, of which the following is a specification.

10 This invention relates to an improved force-feed lubricator having one or more pumps; and it consists in the construction of such a device in which the oil is taken at each suction stroke from a reservoir to the 15 pump or pumps, and discharged by the pump or pumps at every other pressure-stroke through a sight feed conduit, and then returned to the reservoir, a corresponding quantity of oil being at the next pressure-stroke of the pump or pumps delivered 20 out through the discharge-passage or passages to the point or points to be lubricated.

The invention particularly consists in the construction of a series of, preferably, equal 25 pump units, each including a pump cylinder, a plunger, and a reciprocating valve, and in the construction of means for moving the plungers and the valves so as to cause the same to operate in the manner herein-before stated.

The invention further consists in the construction and combination of the various parts as more fully hereinafter described, and particularly pointed out in the claims.

35 In the accompanying drawing, which forms part of this specification, Figure 1 is a vertical cross-section through the entire lubricator according to a preferred embodiment of this invention. Fig. 2 shows a 40 similar section through a separate pump unit the plunger of which is out of operative position. Fig. 3 is a horizontal section through part of a plunger and the driving means thereof. Figs. 4 and 5 show the 45 means for transmitting motion from the driving shafts of the plungers to the valves, said means being shown in two different positions. Figs. 6-9 show vertical sections of a pump unit in four different operative 50 positions thereof. Fig. 10 is a horizontal section of a pump unit showing the valve and its driving means.

Referring to the drawing, 1 indicates the oil reservoir or casing, in which a number 55 of pump units is mounted, one such unit only being shown in the drawing as all are

assumed to be of the same construction. Each pump unit comprises a cylinder 3, a plunger 4 and a valve 8 movable to and fro parallel to the plunger 4. The pump cylinder 3 is provided with a downwardly extending suction pipe 20 extending almost to the bottom of the reservoir 1 said pipe 20 communicating with a passage 21 formed in the cylinder 3 and in turn communicating by way of a circular groove 22 formed in the plunger 4, with the boring of the cylinder 3 containing the valve 8. The cylinder 3 is further provided with a T-shaped passage, connected at 23 with the boring 70 containing the plunger 4 and communicating at 24 and 25 with the boring containing the valve 8. The valve 8 is formed with a recess 26 adapted to connect the passages 21 and 24 with one another. In connection with the recess 26, a transverse passage 27 is formed in the valve said passage being adapted to communicate in a certain position of the valve with the conduit 10 leading to the sight-feed glass 9 open at its lower end into the 80 reservoir. Another transverse passage 28 formed in the valve 8 connects in another position of the valve the passage 25 with a discharge passage 7.

The plungers 4 are driven from a common driving shaft 2 through the intermedium of an eccentric 6 attached to said shaft and a rocking lever 5 pivotally connected to the rod 61 of said eccentric. The rocking lever 5 turns on a pivot 29, carried by a set-screw 30 by means of which the distance of the pivot 29 from the plunger 4 may be adjusted as desired. The connection between the rocking lever 5 and the plunger 4 is effected by means of a thin end portion 31 of 90 the plunger extending through an opening in a transversely extending rib 32 of the rocking lever 5 and being held in place by a pin 33 (Fig. 3).

The valves 8 are driven from the shaft 2 through the intermedium of a common shaft 34 parallel to the shaft 2. The connection between the shafts 2 and 34 consists of a disk 14 attached to the shaft 2 and provided with two lateral projections or pins 15 situated at diametrically opposite points, said connection further including a Geneva stop 13 formed with four recesses at right angles to each other and adapted to be engaged by the pins 15. Between the pins 15 the 105 disk 14 is provided with arced lateral flanges 16 designed to coöperate with the corre-

spondingly curved edges of the Geneva stop. Between the ends of the flanges 16 sufficient space is left for permitting the turning of the Geneva stop 13 when operated by a pin 5 15, as shown in Fig. 5.

Motion is transmitted from the shaft 34 to each of the valves 8 by means of an eccentric 35 attached to the shaft 35, the rod 36 of which is pivotally connected to the end of 10 the valve opposite to the shaft 34.

The operation of the device hereinbefore described is as follows: At each revolution of the shaft 2 the Geneva stop 13 is moved through half a revolution in two equal steps, 15 the Geneva stop being moved a quarter of a revolution at each operation through a pin 15. The Geneva stop 13 is prevented from turning between each two successive movements owing to the engagement between the 20 concave outer edge of an arm of the Geneva stop and one of the flanges 16, as shown in Fig. 4. The Geneva stop is thus moved to and maintained in four different successive positions as the plunger 4 perform two complete 25 cycles of operation. The power transmitting means described are so adjusted with respect to each other as to effect the movement of the Geneva stop just as the plungers are reversed at their one end positions the 30 Geneva stop and thus also the valves being locked in their position while the plungers are moving between their end positions.

The four successive positions of one valve are shown in Figs. 6-9. In Fig. 6, the valve 35 is in its central position while the plunger is performing its suction stroke. Oil will now be taken from the reservoir 1 through the pipe 20, the passage 21 and the groove 22 to the recess 26, by way of said recess to the 40 passage 24, 23 and from thence into the closed chamber in front of the plunger 4. In Fig. 7 the shaft 2 has made half a revolution, the movement of the plunger has just been reversed, and the valve has been moved 45 into its one end position. The oil previously taken in by the pump will now be pressed from the chamber in front of the plunger through the passage 23, 24 and the passage 27 into the conduit 10 carrying the oil to 50 the sight feed glass 9, from which the oil will be returned to the reservoir 1. The shaft 2 having again moved through half a revolution, the plunger 4 will again be reversed and the valve will be in its central 55 position (Fig. 8). Oil will now be taken from the reservoir 1 and delivered into the chamber in front of the plunger in the same way as above described with reference to Fig. 6. After the plunger has again been 60 reversed and the valve has been moved into its opposite end position (Fig. 9), this oil will be forced out from the chamber in front of the plunger through the passage 23, 25 and the passage 28 and delivered into the 65 passage 7 and from thence the oil will be

carried to the point to be lubricated. With the above described construction, it will be seen, that the oil is pressed at every other pressure-stroke to the points to be lubricated and at every other pressure-stroke to 70 the sight-feed conduit. As the amount of oil delivered to the sight-feed conduit is equal to that delivered to the discharge passages the function of the pumps may be observed without the necessity of mounting a 75 sight-feed glass into the discharge-passages whereby air would otherwise enter the oil during its passage to the points to be lubricated.

In force-feed lubricators of the above said 80 kind, the amount of oil to be delivered is usually determined by providing an adjustable clearance or play of the means transmitting motion to the plunger, so as to give the plunger its largest stroke when this play 85 has its smallest value, and vice versa. If, however, a certain pressure must be overcome by the pumps, as for instance, in lubricating cylinders of steam engines or internal combustion engines, part of the oil in the 90 discharge pipe will be forced back into the pump cylinder as the passages of the said pipe are uncovered, the amount of oil being thus forced back depending upon the adjustment of such play or clearance. This 95 will cause the oil pressure within the pipe line to vary at each stroke of the plungers. To overcome said inconvenience the regulation of the length of the plunger stroke according to this invention is effected by means 100 of the set-screw 30. In Fig. 1, the pivot 29 is shown in its uppermost position corresponding to the largest stroke of the plunger. According as the pivot 29 is depressed by 105 turning the screw 30 the length of the plunger stroke will be successively decreased, until when the axis of the plunger 4 coincides with that of the pivot 29 no movement 110 at all will be transmitted to the plunger.

What we claim, and desire to secure by 110 Letters Patent, is as follows:—

1. In a force-feed lubricator the combination with an oil reservoir of a number of pump units mounted in said reservoir, each unit comprising a pump cylinder, a plunger 115 and a reciprocating valve, a common driving shaft for the plungers of said units, another common shaft driven from said first-mentioned shaft by means of a disk mounted on the said first-mentioned shaft and provided with two pins, and a Geneva stop 120 mounted on the said other shaft and having four recesses adapted to be engaged by said pins, said disk and said Geneva stop being provided with coacting guiding means for 125 maintaining the Geneva stop in position after each operation thereof, means for transmitting power from the shaft carrying the Geneva stop to the valves of the pump units, suction pipes and sight-feed conduits con- 130

trolled by the valves, said conduits returning to the oil-reservoir, discharge-passages likewise controlled by said valves, passages formed in the valves for connecting the 5 pumps at each suction stroke with the oil reservoir through said suction pipes, at every other pressure stroke with the sight-feed conduits and at every other pressure stroke with the discharge-passages, the arrangement being such that the valves are moved from one 10 position to another just as the plungers are reversed at their end positions.

2. In a force-feed lubricator the combination with an oil reservoir of a number of 15 pump units, each comprising a pump cylinder, a plunger and a reciprocating valve, a common driving shaft for the plungers of said units, another common shaft for driving the valves of said units, means for transmitting motion from said first-mentioned 20 shaft to said last-mentioned shaft, suction pipes, sight-feed conduits controlled by said valves and returning to the reservoir, discharge passages likewise controlled by said 25 valves, and means for independently adjusting the length of the hub of the plungers, said means comprising a rocking operating

lever for each plunger and means for adjusting the operative length of said rocking lever.

30

3. In a force-feed lubricator the combination with an oil reservoir of a number of pump units, each comprising a pump cylinder, a plunger and a reciprocating valve, a common driving shaft for the plungers of 35 said units, another common shaft for driving the valves of said units, means for transmitting motion from said first-mentioned shaft to said last-mentioned shaft, suction pipes, sight-feed conduits controlled 40 by said valves and returning to the reservoir, discharge passages likewise controlled by said valves, and means for independently adjusting the length of the hub of the plungers, said means comprising a rocking lever 45 for each plunger, each lever being operatively connected to the common driving shaft for the plungers and further connected to the corresponding plunger, and mounted to turn on an adjustably mounted pivot.

50

In testimony whereof we have signed our names.

CARL GUSTAFSON.
KNUT APPELGREN.
